HARRY A. HOUSEMAN AND HAROLD E. HOUSEMAN, OF PHILADELPHIA, PENNSYLVANIA, ASSIGNORS TO STANDARD MACHINE COMPANY, OF PHILADELPHIA, PENNSYLVANIA, A CORPORATION OF PENNSYLVANIA.

CIRCULAR-KNITTING MACHINE.

1,127,768.

Specification of Letters Patent.

Patented Feb. 9, 1915.

Application filed April 15, 1913. Serial No. 781,199.

To all whom it may concern:

Be it known that we, HARRY A. HOUSEMAN and HAROLD E. HOUSEMAN, citizens of the United States, residing at Philadelphia, 5 county of Philadelphia, and State of Pennsylvania, have invented a new and useful Improvement in Circular-Knitting Machines, of which the following is a full, 10 clear, and exact description, reference being had to the accompanying drawings, which form a part of this specification.

The object of our invention is to construct a circular knitting machine for the manufacture of hosiery and especially that type 15 thereof in which the needle cylinder rotates and oscillates while the cam cylinder or ring remains stationary.

The invention comprises a number of novel features, which, in their application, 20 are particularly adapted, but not necessarily confined to machines in which the needle cylinder is the rotatable element.

The invention also comprises the combination and coördination of these novel features 25 with certain mechanism, including the means for controlling and effecting the shift from rotation to oscillation and vice versa, that forms the subject matter of an application filed by Harry A. Houseman, May 17, 1912, 30 Serial No. 697,861, in which the needle cylinder is the stationary element and the cam cylinder the rotary element.

The invention will be understood by reference to the accompanying drawings and the 35 particular description thereof, in which we have shown and described the independently novel features of the present invention as well as certain of the mechanism, adapted from the Harry A. Houseman machine above 40 mentioned, that is coöordinated and combined with said independently novel features.

In the drawings: Figure 1 is a front elevation of a part of the machine, illustrating principally the mechanism for rotating and 45 oscillating the needle cylinder. Fig. 2 is a horizontal section on the line 2—2 of Fig. 1. Fig. 3 is a plan view of a part of the machine. Fig. 4 is a side elevation of the machine, partly broken away. Fig. 5 is a detail sectional view showing the principal mechanism for shifting from rotation to oscillation and vice versa. Fig. 6 is an enlarged sectional plan view of the knitting 50 head and ratchet ring and certain of the

needle actuating mechanism controlled by 55 the ratchet ring. Fig. 7 is a vertical sectional view on the line 7—7—7 of Fig. 6. Fig. 8 is a fragmentary side view of the cam for lowering the rear bank of needles. Fig. 9 is a development comprising a view from 60 the inside of the cams for acting directly upon the needles. Fig. 10 is a similar development comprising a view from the outside of the pickers and the cam for raising the rear bank of needles, the parts being 65 shown in the position they occupy at the end of rotation. Fig. 11 is a view, similar to Fig. 10, showing the parts in the positions they occupy at certain times during the first half of oscillation. Fig. 12 is a view, similar to Figs. 10 and 11, showing the parts in the positions they occupy at certain times during the second half of oscillation.

Referring first to Figs. 4 and 7, *a* is the frame of the machine and *b* the bed plate 75 for the needle cylinder, cam ring and appurtenant mechanism. The needle cylinder *e* has secured to its lower end the driven gear 11 (which is actuated as hereinafter described), resting directly upon the ring *c* 80 within the bed *b*, which ring rests upon the ring *d* secured to the inner lower edge of the bed *b*.

The rotatable needle cylinder is provided with radial slots extending inward from its 85 outer wall, the needles *f*, *g*, extending within these slots and being movable upward therein to render them inactive, as is well understood in the art.

Supported on the top of the bed plate is 90 the cam ring *h* which carries the ordinary knitting cams for actuating the needles.

As is well understood, during the knitting of the leg of the stocking and during the 95 knitting of that part of the stocking between the heel and toe (which we shall call the foot), the needle cylinder is continuously rotating and all the needles are down and in action. During the knitting of the heel and toe, the needle cylinder is oscillated, and the 100 needles *g* extending throughout one-half the circumference of the needle bed (hereinafter referred to as the rear bank of needles) are initially thrown out of action. This is effected by providing the needles *g* with long 105 butts and causing a cam (hereinafter described) to be moved into position to engage all the long butt needles and move them up

in their slots. During the oscillation of the needle cylinder, the needles ⁵ extending throughout the remaining semi-circumference of the needle bed (that is, the front bank of needles) are thrown out of action, one at a time, first at one end of the semi-circumference and then at the other end, and so on alternately until a limited number of needles in the central part of the semi-circumference are in action. The needles are then thrown into action one at a time in the reverse order in which they are thrown out. This operation is effected by means of two sets of pickers hereinafter described and having the construction and operation of the picker forming the subject-matter of the application of Harold E. Houseman, filed June 17, 1912, Serial No. 704,027, and controlled by special mechanism also hereinafter described.

The gear 11 on the knitting cylinder is driven from the gear 12 on the clutch shaft 20, on which are slidably mounted the two pinions 21 and 22, which have sleeves to 25 which are keyed the vertically movable arms 24, 24, which are moved up or down in unison as hereinafter described. The clutch 23 is fixed on the shaft 20, between pinions 21 and 22. The upper pinion 21 is constantly 30 rotated and the lower pinion 22 constantly oscillated. When the arms 24 are moved down, thus engaging the rotary pinion with the clutch 23 and disengaging the oscillatory pinion 22 therefrom, the gear 12 is 35 continuously rotated, thus rotating the needle cylinder. When the arms 24 are elevated, thus disengaging the rotary pinion 21 from the clutch 23 and engaging the oscillatory pinion therewith, the gear 12 is constantly oscillated, thus oscillating the knitting cylinder.

The pinion 21 is constantly rotated by means of a spur gear 25 meshing with the pinion 21. The shaft 26 of the spur gear 25 also carries a bevel gear 27 driven from a bevel pinion 28 on the driving shaft ^t.

The pinion 22 is constantly oscillated by the following means. On the shaft 26 is a crank 29 connected by a link 30 with an arm 31 turning on a post 32. Extending from the hub of the arm 31 is a quadrant 33 engaging the pinion 22.

The arms 24 are secured to a post 60, which has a pair of collars 61 between which 55 extend the forked ends of a lever 62 pivoted between its ends on the frame of the machine. The lever is actuated by means of a double cam 63, 64 secured to a sleeve 67 on the shaft 69. These cams rotate together 60 and may be integral one with another. Each cam has a high part and a low part. The high part of cam 63 is adapted to coact with an arm 65 on the lever 62. The high part of cam 64 is adapted to coact with an arm 66 on the lever 62. When the high part of

cam 63 coacts with the arm 65, the post-engaging end of the lever 62 is moved and held down, thereby moving down the post 60, the arms 24 and the pinions 21 and 22, thereby clutching pinion 21 with the clutch 23 and dictating the rotation of the needle cylinder. When the high part of cam 64 70 coacts with the arm 66, the post engaging end of lever 62 is held up, thereby dictating the oscillation of the needle cylinder. The length of the high part of each of the cams 63 and 64 corresponds with the length of the low part of the other cam, and the arrangement is such that when the high part of one cam starts to ride under its corresponding lever arm, the high part of the other cam starts to recede from its corresponding lever arm. Thus the lever 62 is always in positive engagement with one cam or the other.

The double cam 63, 64, is caused to turn by means of a pattern ratchet wheel 68, also secured to the sleeve 67, which ratchet wheel is turned initially by first turning the sleeve 67 and then by means of a pawl 70. In the Harry A. Houseman application hereinbefore referred to is fully set forth pattern mechanism for initially turning the sleeve 67. This mechanism is capable of application to the present machine and need not therefore be described. It is sufficient to say that just before it is desired to change from rotation to oscillation, the cam shaft 77 (which is geared to the sleeve 67 by means of the intermeshing pinions 78 and 79) is given a partial turn, thereby turning the sleeve 67 together with the double cam 63, 64 and the ratchet wheel 68.

The pawl 70 is constantly reciprocated by means to be hereinafter described. The ratchet wheel 68 has a number of teeth, all of uniform length except one, 80, which is substantially longer than the others. During oscillation of the cam cylinder, the pawl 70 plays upon the long teeth, its extent of movement being insufficient to cause it to drop back of the same. Consequently, it is inoperative to turn the ratchet wheel 68. But after the ratchet wheel has been given the initial turn just described, the long tooth is advanced to such position that on the next reciprocation of the pawl 70 it drops back of the long teeth 80 and proceeds to turn the ratchet-wheel, together with the double cam 63, 64.

As the pawl 70 engages and pushes the next teeth of the ratchet 68, the high part of cam 63 recedes from the lever arm 65 and the high part of cam 64 engages lever arm 66, thereby lifting the post-engaging end of lever 62, clutching the lower or oscillatory pinion 22 to the clutch shaft 20 and unclutching the rotary pinion 21, and causing the needle cylinder to oscillate.

The constant reciprocation of the pawl 70

is erected by securing to the hub of lever 31 a section of a bevel pinion 81 which drives a similar pinion 82 on the shaft 69. To this shaft is secured a holder 83 carrying the pawl 70.

At the same time that the machine is shifted from rotation to oscillation, it becomes necessary to throw out of action the rear bank of needles *g*. Before particularly describing the mechanism for effecting the movement, reference will be made to the pattern mechanism and needle actuating mechanism embodying the novel features of the present invention.

By reference to Figs. 6 and 7 it will be noticed that a ring or wheel *i* rests upon an annular flange projecting from the bed plate *b*. This ring is provided on its periphery with a series of teeth, most of which are of uniform length. It will be noted, however, that one of them, marked *z*, is of twice the length of the shorter teeth, while two pairs of teeth *y*, *y'* and *x*, *x'* are of intermediate length, each of them being half again as long as one of the shorter teeth. This ratchet wheel is operable by two pawls—one, the main pawl *j*, which is the ordinary actuating pawl, and the other, the supplemental pawl *k*, which actuates the ratchet ring *i* at only one point in a complete rotation, as hereinafter described.

The pawl *j* is supported and actuated as follows: A ring 101 (see Fig. 7) is loosely inserted in a recess formed in the bed plate *b* and rests on the ring *d*. This ring has an arm 102 on which is pivoted the pawl *j*, the pawl being held in operative relation with the ratchet ring *i* by means of a spring 103 (see Fig. 3). The arm 102 also carries a pin 104 (see Fig. 4), on which is a roller 105 that enters the cam groove (see Fig. 2) formed in the upper surface of the spur gear 23. This groove is formed by an inner cam 106 and an outer cam 107, which cams through the roller 105 and arm 102, oscillate the ring 101 back and forth a distance equal to the desired throw of the pawl *j*. The motion thus imparted to the pawl is such that its complete forward or actuating throw is effected by two successive movements, while its retraction is effected by a single movement. In actuating the short teeth, the pawl is retracted to such an extent that the first forward movement does not operatively engage the tooth in advance thereof, the tooth being engaged and the ratchet ring operated on the second forward movement of the pawl. A tooth of middle length, *x* or *y*, is, however, actuated on the first forward movement. The long tooth *z*, however, is of such length that the pawl *j*, in its retraction, will not drop back of it until the ratchet ring *i* is turned by the supplemental pawl *k*, but will play idly back and forth on the long tooth, this condition

existing during the rotary movement of the needle cylinder, when the ratchet ring *i* is stationary.

The two successive forward movements of the pawl *j* are so timed that, during oscillation of the needle cylinder, one occurs in the first part of the forward oscillation of the needle cylinder, while the other occurs during the last part of the forward oscillation of the needle cylinder. Thus, when one of the short teeth, or the long tooth *z*, is actuated, the ratchet ring *i* turns during the latter part of the forward oscillation of the needle cylinder; while if one of the teeth *x*, *x'* or *y*, *y'*, of intermediate length is actuated, the ratchet ring *i* turns during both parts of the forward oscillation of the needle cylinder.

The supplemental pawl *k* (see Figs. 3 and 4) is pivoted on one end of the lever 110 and is held in operative relation with the ratchet ring *i* by the spring 111. The lever 110 is pivoted between its ends on a bracket secured to the main frame, its other end being pivoted to one end of a link 112. The other end of the link is pivoted to the upper end of a rock arm 113, the lower end of the arm being pivoted on the main frame. This arm carries a projection which is engaged by a cam 114 on the cam shaft 77.

As before described, just before the shift from rotation to oscillation, the cam shaft 77 is turned to turn (by means of gears 78 and 79 and sleeve 67) the ratchet wheel 68 into position to cause the pawl 70 to drop back of the long tooth 80 of the ratchet wheel 68. At the next turn of the machine, the pawl 70 actuates the long tooth 80 of the ratchet wheel 68, thereby turning the cam shaft 77 to such position that the cam 114, through the arm 113, link 112 and lever 110, causes the supplemental pawl *k* to push one of the short teeth in advance of the long tooth *z* of the ratchet ring *i* and turn the ratchet ring a distance of one short tooth, allowing the main pawl *j* to drop back of the long tooth *z* so that, on the next forward movement of the main pawl *j*, it will actuate the long tooth *z* in the same manner as it normally actuates one of the short teeth.

During the actuation of the next tooth of ratchet wheel 68 by the pawl 70, the pinions 21 and 22 are shifted to cause the oscillatory pinion 22 to operate the clutch shaft, as hereinafore described. At the same time the pawl *j* actuates the long tooth *z* of the ratchet ring *i*, thereby operating the mechanism for lifting the rear bank of needles *g* out of action and moving into operative position the pickers for lifting out of action the needles *f*, one at a time, as hereinbefore mentioned. This mechanism will now be described.

On the ratchet ring *i* is a cam *m* which is in line of travel of an arm 120 on a rock

shaft 121 turning in a bracket on the cam ring. The shaft 121 carries a cam arm 122, which, by means of the spring 123, is normally held out of the path of the long butts 5 of needles *g* of the rear bank, but which, when the ratchet ring is given the shift just described, is swung up, by the cam *m*, arm 120, and rock shaft 121, into the path of the long butts of the needles *g* of the rear 10 bank, thereby elevating these needles in their slots and throwing them out of action.

At the same time the cam *n* on the ratchet ring *i* passes beyond the lever 135, which moves the pickers 130 into operative position, as will now be described.

The pickers are two in number, one for moving out of action, one at a time, needles at one end of the front bank of needles *f*, the other for moving out of action, one at 20 a time, the needles at the other end of the front bank of needles. These pickers are more fully described and shown in the Harold E. Houseman application hereinbefore referred to. Briefly (see Figs. 9 and 10), each picker comprises a picker arm or cam 25 130 which has two pins 132, 133, extending respectively into two slots on the frame 131. In the oscillation of the needle cylinder, the butt of the particular needle which at any 30 given oscillation is in advance strikes the end cam surface of the picker 130 and pushes the same in the direction of movement of the needle, the pins sliding in the slots and causing the needle-engaging end 35 of the picker to rise and lift the said needle out of action and at the same time swing so as to allow the needle butt to slide off the end cam surface of the picker. The butts of the other needles pass under the overhang- 40 ing end of the picker, and as soon as these needles pass beyond the picker a spring 138 draws the picker back to its initial position ready to engage the first needle in action on the next oscillation of the needle cylinder.

45 When it is desired to move the pickers into inoperative position, as during the rotation of the needle cylinder, the pickers are elevated so that the butts of all the needles pass under the overhanging ends 50 thereof. This is accomplished by providing one of the pins 132 of each picker with a head 134 (see Fig. 6), which is engaged, and adapted to be actuated, by a lever pivoted on the cam ring *h*. The lever engag- 55 ing the pin 132 of one picker is marked 135, while the lever engaging the pin 132 of the other picker is marked 136. Lever 136 is a two-armed lever and is connected by a pin and slot connection 137 with the lever 135, 60 which is a three armed lever. The third arm of lever 135 is in line of travel of the cam *n*.

During rotation, the cam *n* engages the lever 135 and holds levers 135 and 136 in 65 such position that the pins 132, 132, of the

two pickers are held in the inner ends of the slots in the frame 131 (see Fig. 10), thus holding the pickers up in inoperative position, so that the butts of all the needles 70 an- derride the overhanging head of the pickers and operatively engage the ordinary knitting cams *s* (see Fig. 9). As before stated, when the pawl *j* actuates the first short tooth *w* behind the long tooth *z* of the ratchet ring *i*, the cam *n* passes beyond the lever 135, and a spring 139, connected with lever 136, pulls both levers out of operative position, allowing the springs 138 to move the pickers 130 into operative position to throw out of action the needles of the front 80 bank, one at a time, as hereinbefore described.

The cam *n* and the mechanism controlled thereby for holding the pickers out of action are not absolutely necessary; for even 85 if no means were provided to hold the pickers out of operative position, one of them would, during rotation, ride over the butts of the needles; but this would create needless wear and tear both upon the needles 90 and one of the pickers, which is obviated by the mechanism above described.

It will be noted that as the ratchet ring *i* is turned by the pawl *j*, so also is the ratchet wheel 68 turned by the pawl 70. It is de- 95 sirable, for reasons which are not material to specify in connection with a description of our present invention, to stop the rotation of the ratchet wheel 68. We have provided for rendering the pawl 70 inoperative by 100 mechanism actuated on the next turn of the ratchet ring *i*—that is, when the pawl *j* engages and pushes the tooth *w* back of the tooth *z*. A dog or guard 140 (see Fig. 4) is pivoted on the frame. When the guard is 105 dropped into engagement with the pawl 70, it tilts the pawl out of engagement with the ratchet wheel 68, so that the pawl, on subsequent reciprocations, is ineffective to turn the ratchet wheel. A link 141 connects 110 the guard 140 with an arm 142 on a rock shaft 143. An arm 144 on the rock shaft is in line of travel of a cam *o* on the ratchet ring *i*. Prior to the engagement of tooth *w* of the ratchet ring *i* by the pawl *j*, the cam *o* holds up the arm 144, thereby disengag- 115 ing the guard 140 from the pawl 70; but when the ratchet ring *i* is turned by the engagement of pawl *j* with tooth *w*, the cam *o* passes from under the arm 144, allowing the 120 guard 140 to drop and render the pawl 70 inoperative.

While the pawl *j* is turning the teeth of the ratchet ring between tooth *w* and the tooth *z* of intermediate length, the needle cylinder continues to oscillate, and the needles *f* of the front bank continue to be thrown out of action one at a time, as before described, until a comparatively few needles (say about one-third of the number in the 130

rear bank) remain in operation. This forms one half of the fashioned fabric composing the heel or toe of the stocking.

It is now necessary to return the needles *f* of the front bank, thus rendered inactive, into operative position, one at a time, in approximately the reverse order in which they are thrown out by the pickers 130. This is preferably accomplished, as is well known in the art, by allowing the pickers 130 to continue to operate to move the needles out of action one at a time, and at the same time render operative a pair of pickers which will move the needles into action two at a time, the net result of which is to move the needles into action approximately in the reverse order in which they were thrown out. These pickers and their actuating mechanism will now be described.

The pickers 150, 150 for moving the needles into action are shown in Figs. 6, 9 and 10, and we prefer to construct them on the same principle as pickers 130. 151, 151 are the frames containing the slots into which the pins 152, 153, on the pickers extend. It will be noted, however, that the positions of pickers 150, 150, are inverted relatively to the pickers 130, 130, so that when their end cam faces engage the butts of the needles *f*, they draw the needles down in their slots into operative position. The end cam face of each picker 150, 150, is made somewhat longer than the end cam face of each picker 130, 130, so that the butts of two needles will engage therewith before the picker is turned into position to allow the butts of the needles following to over ride the underhanging end of the picker.

It will be observed that there is added to each picker a lever 154, which has a slot engaging the pin 152. Each lever 154 has a projection engaging a pin 155 on the frame 151. To the lower end of each lever 154 is pivoted a lever 156, pivoted between its ends, at 157, on the cam ring, and having on its end a curved rack engaging a similar rack on the toothed lever connected with the other picker. While the pickers 150 are in operation, the downward movement of each picker to throw a pair of needles into action causes the corresponding lever 154 to swing on its pivot into line of travel of a projection 158 on the needle cylinder, which, on the return movement of the needle cylinder, strikes the lever 154 and restores the picker to operative position. The needle cylinder, at each oscillation, describes nearly a complete rotation, so that the same projection 158 actuates both pickers.

The lever 156 connected with one of the pickers has a hub provided with an arm 159 having a pin 170 in line with a cam *p* extending slightly more than half way around the ratchet ring *i*. During rotation, and also during that part of the oscillation in

which the fabric is being narrowed, the cam *p* underrides the arm 159. When the cam *p* passes under arm 159, the latter draws down the lever 156 and also the lever 154 pivoted thereto, the projection on lever 154 sliding along the pin 155, thus drawing down the corresponding picker 150 into inoperative position. By reason of the intermeshing racks on the two levers 156, both pickers 150 are withdrawn from operation 70 simultaneously. This not only draws the pickers out of operation, but pulls down the levers 154 so that the projection 158 on the needle cylinder will clear the same. The pickers 150, 150 continue to be held out of 80 operative position as long as the cam *p* underrides the arm 159.

So far in the described operation of the ratchet ring the cam *p* has been underriding the arm 159, and the pickers 150, 150, have 85 been held inactive. As soon, however, as the pawl *j* actuates the tooth *x*, the end of cam *p* passes from under arm 159, which, under the influence of spring 174, drops and swings up the levers 154 into position to be 90 moved into operation by the projection 158. Owing to the length of the tooth *x*, this operation occurs on the first part of the forward movement of the pawl *j*, during which the needle cylinder is on its first half turn 95 in one direction, and, therefore, at the time levers 154 are moved into the path of travel of the projection 158, the latter is approximately on the side of the knitting head opposite the pickers 150, and thus, by actuating the levers 154 at this time, ample margin is allowed. The pawl *j* continues to actuate the ratchet ring *i* during the knitting of the remainder of the fashioned fabric-forming the heel or toe, both pairs of 100 pickers remaining operative during this time; but no mechanism is actuated by the ratchet ring until the pawl *j* actuates the tooth *u*, which is the second tooth before the tooth *y*. At this time the cam *o* rides 110 under the arm 144, lifting the guard 140 and again allowing the pawl 70 to drop into operative relation with the ratchet wheel 68. In the continued turning movement of the ratchet ring *i*, the pawl *j* drops back of the 115 tooth *y* of intermediate length, and when the ratchet ring is turned by the actuation of tooth *y* the following operations occur. First, the pawl 70 turns ratchet wheel 68 into position to effect the disengagement of 120 the oscillating pinion 22 from the clutch shaft 20 and the engagement of the rotary pinion 21 therewith. Second, the cam *p* rides under the arm 159, withdrawing the pickers 150 from operative position, as before described. Third, a cam *r* on the ratchet ring actuates mechanism for moving all the inactive needles into operative position. At this time the needles of the rear bank are in inoperative position, and four 130

of the needles of the front bank have not yet been moved into operative position. The mechanism for effecting this operation will now be described (see Figs. 7 and 8).

Pivoted on the ring *c* is a lever 161 carrying at its upper end, and on its inside face, a needle-depressing cam 160. The upper end of the lever 161 is shaped to conform to the cam 160. Extending outward from the lever 161 is a pin 162 extending through a slotted lever 163 pivoted on a bracket on the lever 161. Outside the lever 163 a nut 164 is threaded on the pin 162. The lever 163 carries a cam 165 which is in line of travel of the cam *r*. A spring 166 is coiled about the pin 162 between the levers 161 and 163. A spring 167 normally holds the lever 161 in the retracted position in Fig. 7. When the pawl *j* actuates the tooth *y*, the cam *r* under- 20 rides the cam 165 and swings the lever 163 inwardly. Through the medium of spring 166 the lever 161 is pushed inwardly, the location of the lever 161 being such that at this time the needles *f*, with the short butts, which are already in action, are passing in front of the cam 160. The cam 160 swings over these butts and against the outer wall of the needle cylinder and in line of travel of the butts of all the needles that are out of 25 action, so that, as the needle cylinder continues to turn, the butts of the last named needles successively engage the cam 160 and are moved down thereby into operative position, as shown in Fig. 8. If, for any reason, 30 all the needles should be in inoperative position, the cam 160, under the impetus of spring 166, would first swing against the short butt needles *f* and in line of travel of the long butts of the needles *g*, and after en- 35 gaging the long butt needles *g* and drawing them down, would swing farther inward into the path of travel of the short butt needles *f* and draw them down. On the next forward throw of the pawl *j*, it engages the 40 tooth *y'* and causes the cam *n* to engage the lever 135 and render the pickers 130, 130 inoperative as before described. The next tooth of the ratchet ring *i* is a short one and the actuation of this tooth by the pawl *j* 45 actuates no mechanism. Thereafter, during rotation, or during the knitting of the circular portions (leg and foot) of the stocking, the pawl *j* plays idly upon the long tooth *z*. In the meantime the pawl 70 has: 50 turned the ratchet wheel 68 into such position that the pawl 70 plays idly on the long tooth 80 of ratchet wheel 68, until the ratchet wheel 68 is turned from the pattern mechanism to allow pawl 70 to again operate it as before described. This completes the cycle 55 of operations of the machine.

It is of importance that the arm 159 controlling the pickers 150 should be actuated to withdraw the pickers 150 at the proper time; and to insure this, regardless of the

proper coordination between arm 159 and cam *p*, the following mechanism is provided. By reference to Figs. 6 and 7 it will be noted that the outer end of the arm 159 carries not only the short pin 170 which cooperates with the cam *p*, but also an offset overriding a long pin 171, which extends vertically through the cam ring *h* and bed plate *b* and has on its end a head 172 located in a recess in the bed plate. A lever 173 (see also Fig. 75 4) is pivoted between its ends on the bed plate, one end of the lever being curved upward and extending under the head 172 while its other end carries a pin which extends under the arm 24 supporting the 80 rotary pinion 21 (see Fig. 5). It has been hereinbefore stated that the cam *p* rides under the pin 170 of the arm 159 to effect the withdrawal from operative position of the 85 needle pickers 150 at the same time that the rotary pinion 21 is moved down into engagement with the clutch shaft 20. As the pinion 21 is lowered, its supporting arm 24 depresses the corresponding end of lever 173, thereby raising the other end of lever 173, 90 which lifts the pin 171. Normally this will occur after the lifting of arm 159 by the cam *p*; but if, for any reason, the cam *p* should fail to act, the arm 159 will nevertheless be lifted, by the pin 171, before the machine 95 starts to rotate.

In describing the construction of the machine we have incidentally described the operation of the various parts in their proper sequence; but it may be desirable; at the 100 risk of repetition, to summarize the operation briefly, following the sequence of operations throughout a complete rotation of the ratchet ring *i*. Assume the machine to be engaged on rotary work, at which time the 105 pawl *j* is playing idly on the long tooth *z* of the ratchet wheel *i* and the pawl 70 is playing idly on the long tooth of the ratchet wheel 68. As soon as the pattern mechanism dictates the conclusion of the rotary work; 110 the ratchet wheel 68 is turned thereby to allow the pawl 70 to drop back of the long tooth 80. Thereupon the pawl 70 actuates the long tooth 80 of the ratchet wheel 68 and at the same time the pawl *h* is actuated from 115 the shaft 77 to turn the ratchet ring *i* to allow the pawl *j* to drop back of the long tooth *z*. On the next turn of the machine, the pawl 70 turns the ratchet wheel 68 to cause the shift from rotation to oscillation: 120 while the pawl *j* actuates the long tooth *z* of the ratchet ring *i*, causing the cam *m* to dictate the withdrawal from active position of the rear bank of needles *g*, and causing the cam *n* to pass beyond the levers controlling 125 the pickers 130 for moving out of operative position, one at a time, the needles *f* of the front bank: permitting said pickers to move into position to operate. At the next oscillation of the machine the pawl *j* actu- 130

ates the tooth *w* of the ratchet ring *i*, causing the cam *o* to release the mechanism for rendering pawl 70 inactive, thus stopping the rotation of ratchet wheel 68.

As the machine continues to oscillate, the pickers 130 continue to move out of action the needles *f* of the front bank, one at a time, gradually narrowing the fabric, and the pawl *j* continues to rack the teeth of the ratchet ring until it reaches the tooth *x*, at which time the smallest number of needles are in operation and the fabric is at its narrowest width. The actuation of the tooth *x* causes the cam *p* to pass beyond the arm 159, thereby causing the pickers 150 to move into operative position. Thereafter, during the continued oscillation of the machine, the pickers 150 and 130, by their combined operation, gradually move into operative position the needles *f* that have been previously rendered inoperative, thereby gradually widening the fabric. While the tooth *x'* is shown as of the same length as tooth *x*, this simply results in an earlier and longer throw of the ratchet ring than would be the case if the tooth *x'* were of the same length as the shorter teeth, but the operation of the machine would not otherwise be changed. The tooth *x'* may, therefore, be made short, but it is shown as of the same length as tooth *x* in order that these two teeth may be of the combined length of three short teeth, thus facilitating the laying out and cutting of the ratchet wheel. When tooth *u* is actuated, the cam *o* effects the lifting of the guard 140 from pawl 70, allowing the latter to again operate to turn the ratchet wheel 68. When the tooth *y* is actuated, the pawl 70 turns the ratchet wheel 68 to cause the shift from oscillation to rotation; while the cam *r* underides the cam 153, operating the mechanism to move into operative position all the needles that at this time are inoperative, and the cam *p* engages and lifts the arm 159, thereby moving the pickers 150 into inoperative position, the arm 159 also being lifted by the pin 171 controlled from the lever 24 supporting the rotary pinion 21. The actuation of tooth *y'* causes the cam *n* to engage the levers controlling the pickers 130, causing the latter to be moved into inoperative position. This completes the cycle of operations.

After the pawl *j* actuates the tooth before the long tooth *z*, the pawl *j* plays idly on the face of the long tooth until, at the conclusion of the rotary work, the length of which is controlled by the pattern mechanism not shown, the latter actuates the cam shaft 77 and ratchet wheel 68, thereby again rendering the pawl 70 operative to engage the long tooth 80, whereupon the pawl *k* turns the ratchet ring *i* into position to render the pawl *j* again operative, and the

cycle of operations above described is resumed.

Having now fully described our invention, what we claim and desire to protect by Letters Patent is:

1. In a circular knitting machine, in combination, a relatively rotatable needle cylinder, a relatively stationary cam ring, rotary driving means, oscillatory driving means, shifting mechanism for alternately connecting the two driving means with the needle cylinder, a ratchet ring, means to turn the same during oscillation of the needle cylinder, cam mechanism adapted to move the rear bank of needles into and out of operative position, pickers adapted to move certain needles of the front bank successively out of operative position, pickers adapted to successively move into operative position needles previously rendered inoperative, picker-controlling means, pattern controlled mechanism connected with and adapted to partially control the operation of the shifting mechanism, other devices adapted to partially control the operation of the shifting mechanism, and cams carried by the ratchet ring adapted, as the ratchet ring is turned by its turning means, to control the operation of said needle actuating cam mechanism, picker controlling means, and the last named devices.

2. In a circular knitting machine, in combination, a relatively rotatable needle cylinder, a relatively stationary cam ring, rotary driving means, oscillatory driving means, shifting mechanism for alternately connecting the two driving means with the needle cylinder, a ratchet ring, means to turn the same during oscillation of the needle cylinder, cam mechanism adapted to move the rear bank of needles into and out of operative position, pickers adapted to move certain needles of the front bank successively out of operative position, pickers adapted to successively move into operative position needles previously rendered inoperative, picker controlling means, and cams carried by the ratchet ring and adapted, as the ratchet ring is turned, to control the operation of said needle-actuating cam mechanism and picker controlling means.

3. In a circular knitting machine, in combination, a relatively rotatable needle cylinder, a relatively stationary cam ring, rotary driving means, oscillatory driving means, shifting mechanism for alternately connecting the two driving means with the needle cylinder, a ratchet ring, means to turn the same during oscillation of the needle cylinder, cam mechanism adapted to move the rear bank of needles into and out of operative position, pattern controlled mechanism connected with and adapted to partially control the operation of the shifting mechanism, other devices adapted to

- 8
- partially control the operation of the shifting mechanism, and cams carried by the ratchet ring adapted, as the ratchet ring is turned by the turning means, to control the 5 operation of said cam mechanism.
4. In a circular knitting machine, in combination, a relatively rotatable needle cylinder, a relatively stationary cam ring, rotary driving means, oscillatory driving 10 means, shifting mechanism for alternately connecting the two driving means with the needle cylinder, cam mechanism adapted to move the rear bank of needles into and out of operative position, pickers adapted to 15 move certain needles of the front bank successively out of operative position, pickers adapted to successively move into operative position needles previously rendered inoperative, picker-controlling means, pattern controlled mechanism connected with and adapted to partially control the operation 20 of the shifting mechanism, other devices adapted to partially control the operation of the shifting mechanism, and cams and 25 connections thereto operable during oscillation of the needle cylinder, said cams adapted to control the operation of said cam mechanism, picker controlling means and the last named devices.
- 30 5. In a circular knitting machine, in combination, a relatively rotatable needle cylinder; a relatively stationary cam ring, rotary driving means, oscillatory driving means, shifting mechanism for alternately 35 connecting the two driving means with the needle cylinder, a ratchet wheel, having a relatively long tooth and a number of relatively short teeth, included in said shifting mechanism, a pawl actuating 40 the ratchet wheel, a ratchet ring and a main pawl for actuating it, means to operate the main pawl, pattern-controlled mechanism adapted to turn the ratchet wheel to permit its actuating pawl to operatively engage its long tooth, connections from the 45 pattern controlled mechanism, adapted to render the main pawl operative to turn the ratchet ring, needle actuating devices, and cams carried by the ratchet ring and adapted, 50 as the ratchet ring is turned by the main pawl, to control the operation of the needle actuating devices.
6. In a circular knitting machine, in combination, a relatively rotatable needle cylinder, a relatively stationary cam ring, rotary driving means, oscillatory driving 55 means, shifting mechanism for alternately connecting the two driving means with the needle cylinder, a ratchet wheel, having a relatively long tooth and a number of relatively short teeth, included in said shifting mechanism, a pawl actuating the ratchet wheel, a ratchet ring and a main pawl for 60 actuating it during oscillation of the needle cylinder, means to operate the main pawl, 65
- ing the two driving means with the needle pattern controlled mechanism adapted to turn the ratchet wheel to permit its actuating pawl to operatively engage its long tooth preliminarily to the shift from rotation to 70 oscillation, connections from the pattern controlled mechanism adapted to render the main pawl operative to turn the ratchet ring, needle actuating devices, mechanism adapted to render the ratchet wheel pawl 75 inoperative, and cams carried by the ratchet ring and adapted, as the ratchet ring is turned by the main pawl, to control the operation of said needle actuating devices and the last named mechanism.
- 80 7. In a circular knitting machine, in combination, a relatively rotatable needle cylinder, a relatively stationary cam ring, rotary driving means, oscillatory driving means, shifting mechanism for alternately 85 connecting the two driving means with the needle cylinder, a ratchet wheel included in said shifting mechanism, a pawl actuating the ratchet wheel, a ratchet ring and a main pawl for operating it, means 90 to operate the main pawl, pattern controlled mechanism adapted to effect driving engagement between the ratchet wheel and its pawl preliminarily to the shift from rotation to oscillation, pattern controlled 95 mechanism adapted to render the main pawl operative to turn the ratchet ring, needle actuating devices, and cams carried by the ratchet ring and adapted, as the ratchet ring is turned by the main pawl, to control 100 the operation of the needle actuating devices.
8. In a circular knitting machine, in combination, a relatively rotatable needle cylinder, a relatively stationary cam ring, rotary driving means, oscillatory driving 105 means, shifting mechanism for alternately connecting the two driving means with the needle cylinder, a ratchet wheel included in said shifting mechanism, a pawl actuating the ratchet wheel, a ratchet ring and a main 110 pawl for operating it, means to operate the main pawl, pattern controlled mechanism adapted to effect driving engagement between the ratchet wheel and its pawl preliminarily to the shift from rotation to oscillation, pattern controlled mechanism adapted to render the main pawl operative to turn the ratchet ring, needle actuating devices, mechanism adapted to disconnect the driving connection between the ratchet wheel and its pawl, and cams carried by the ratchet ring and adapted, as the ratchet ring is turned by the main pawl, to control the 115 operation of the needle actuating devices and the last named mechanism.
- 120 9. In a circular knitting machine, in combination, a relatively rotatable needle cylinder, a relatively stationary cam ring, rotary driving means, oscillatory driving means, shifting mechanism for alternately connect- 125
- 130

- cylinder, a ratchet ring, a main pawl for actuating it, and operating means for the main pawl, pattern controlled mechanism connected with and adapted to partially control the operation of the shifting mechanism, pattern controlled mechanism adapted to render the main pawl operative to turn the ratchet ring, needle actuating devices, other mechanism adapted to partially control the operation of the shifting mechanism, and cams carried by the ratchet ring and adapted, as the ratchet ring is turned by the main pawl, to control the operation of the needle actuating devices and the last named mechanism.
10. In a circular knitting machine, in combination, a relatively rotatable needle cylinder, a relatively stationary cam ring, rotary driving means, oscillatory driving means, shifting mechanism for alternately connecting the two driving means with the needle cylinder, a ratchet wheel, having a relatively long tooth and a number of relatively short teeth, a main pawl and a supplemental pawl for actuating the ratchet ring, connections from the needle cylinder driving mechanism for actuating the main pawl, pattern-controlled mechanism adapted to turn the ratchet wheel to permit its actuating pawl to operatively engage its long tooth and adapted also to activate said supplemental pawl to turn the ratchet ring to permit said main pawl to operatively engage its long tooth, needle actuating devices, and cams carried by the ratchet ring and adapted, as the ratchet ring is turned by the main pawl, to control the operation of said needle actuating devices.
11. In a circular knitting machine, in combination, a relatively rotatable needle cylinder, a relatively stationary cam ring, rotary driving means, oscillatory driving means, shifting mechanism for alternately connecting the two driving means with the needle cylinder, a ratchet wheel, having a relatively long tooth and a number of shorter teeth, included in said shifting mechanism, a pawl actuating the ratchet wheel, a ratchet ring having a relatively long tooth and a number of relatively short teeth, a main pawl adapted to play back and forth on the long tooth of the ratchet ring during rotation of the needle cylinder and to activate the shorter teeth during oscillation of the needle cylinder, a supplemental pawl for preliminarily actuating the ratchet ring to render the main pawl operative, means to operate the main pawl, pattern controlled mechanism adapted to turn the ratchet wheel to permit its actuating pawl to operatively engage its long tooth preliminary to the shift from rotation to oscillation and adapted also to actuate said supplemental pawl to turn the ratchet ring to permit the main pawl to operatively engage its long tooth, needle actuating devices, mechanism adapted to render the ratchet wheel pawl inoperative, and cams carried by the ratchet ring and adapted, as the ratchet ring is turned by the main pawl, to control the operation of said needle actuating devices and the last named mechanism.
12. In a circular knitting machine, in combination, a relatively rotatable needle cylinder, a relatively stationary cam ring, rotary driving means, oscillatory driving means, shifting mechanism for alternately connecting the two driving means with the needle cylinder, a ratchet wheel included in said shifting mechanism, a pawl actuating the ratchet wheel, a ratchet ring, having a relatively long tooth and a number of relatively short teeth, a main pawl adapted to play back and forth on said long tooth during rotation of the needle cylinder and to activate the shorter teeth during oscillation of the needle cylinder, a supplemental pawl for preliminarily actuating the ratchet ring to render the main pawl operative, means to operate the main pawl, pattern controlled mechanism adapted to effect driving engagement between the ratchet wheel and its pawl preliminary to the shift from rotation to oscillation and also to actuate the supplemental pawl to turn the ratchet ring to render the main pawl operative, needle actuating devices, and cams carried by the ratchet ring and adapted, as the ratchet ring is turned by the main pawl, to control the operation of said needle actuating devices.
13. In a circular knitting machine, in combination, a relatively rotatable needle cylinder, a relatively stationary cam ring, rotary driving means, oscillatory driving means, shifting mechanism for alternately connecting the two driving means with the needle cylinder, a ratchet wheel included in said shifting mechanism, a pawl actuating the ratchet wheel, a ratchet ring, having a relatively long tooth and a number of relatively short teeth, a main pawl adapted to play back and forth on said long tooth during rotation of the needle cylinder and to activate the shorter teeth during oscillation of the needle cylinder, a supplemental pawl for preliminarily actuating the ratchet ring to render the main pawl operative, means to operate the main pawl, pattern controlled mechanism adapted to effect driving engagement between the ratchet wheel and its pawl preliminary to the shift from rotation to oscillation and also to actuate the supplemental pawl to turn the ratchet ring to render the main pawl operative, needle actuating devices, mechanism adapted to render the ratchet wheel pawl inoperative, and cams carried by the ratchet ring and adapted, as the ratchet ring is turned by the main pawl, to control the operation of said needle actuating devices.

carried by the ratchet ring and adapted, as the ratchet ring is turned by the main pawl, to control the operation of said needle actuating devices and the last named mechanism.

14. In a circular knitting machine, in combination, a relatively rotatable needle cylinder, a relatively stationary cam ring, rotary driving means, oscillatory driving means, shifting mechanism for alternately connecting the two driving means with the needle cylinder, a ratchet ring having a relatively long tooth and a number of shorter teeth, a main pawl adapted to play back and forth on the long tooth during rotation of the needle cylinder and to actuate the shorter teeth during oscillation of the needle cylinder, a supplemental pawl for preliminarily actuating the ratchet ring to render the main pawl operative, means to operate the main pawl, pattern controlled mechanism connected with and adapted to partially control the operation of the shifting mechanism, connections from the pattern controlled mechanism adapted to operate the supplemental pawl, needle actuating devices, other devices adapted to partially control the operation of the shifting mechanism, and cams carried by the ratchet ring and adapted, as the ratchet ring is turned by the main pawl, to control the operation of the needle actuating devices and the last named mechanism.
15. In a circular knitting machine, in combination, a relatively rotatable needle cylinder, a relatively stationary cam ring, rotary driving means, oscillatory driving means, shifting mechanism for alternately connecting the two driving means with the needle cylinder, a ratchet ring arranged concentric with the needle cylinder and having a relatively long tooth and a number of shorter teeth, a pawl actuating the ratchet ring and adapted, during rotation of the needle cylinder, to play back and forth on the long tooth, pattern controlled mechanism adapted to effect actuating engagement of the pawl with the long tooth, cam mechanism adapted to move the rear bank of needles into and out of operative position, pickers adapted to move certain needles of the front bank successively out of operative position, pickers adapted to successively move into operative position needles previously rendered inoperative, picker controlling means, pattern controlled mechanism connected with and adapted to partially control the operation of the shifting mechanism, other devices adapted to partially control the operation of the shifting mechanism, and cams carried by the ratchet ring and adapted, as the ratchet ring is turned by the pawl, to control the operation of said needle-actuating cam mechanism, picker controlling means, and the last named devices.

16. In a circular knitting machine, in combination, a relatively rotatable needle cylinder, a relatively stationary cam ring, rotary driving means, oscillatory driving means, shifting mechanism for alternately connecting the two driving means with the needle cylinder, a ratchet ring arranged concentric with the needle cylinder and having a relatively long tooth and a number of shorter teeth, a pawl actuating the ratchet ring and adapted, during rotation of the needle cylinder, to play back and forth on the long tooth, pattern controlled mechanism adapted to effect actuating engagement of the pawl with the long tooth, needle actuating devices, pattern controlled mechanism connected with and adapted to partially control the operation of the shifting mechanism, other mechanism adapted to partially control the operation of the shifting mechanism, and cams carried by the ratchet ring and adapted, as the ratchet ring is turned by the pawl, to control the operation of the needle actuating devices and the last named mechanism.

17. In a circular knitting machine, in combination, a relatively rotatable needle cylinder, a relatively stationary cam ring, rotary driving means, oscillatory driving means, shifting mechanism for alternately connecting the two driving means with the needle cylinder, a ratchet ring arranged concentric with the needle cylinder and having a relatively long tooth and a number of shorter teeth, a pawl actuating the ratchet ring and adapted, during rotation of the needle cylinder, to play back and forth on the long tooth, pattern controlled mechanism adapted to effect actuating engagement of the pawl with the long tooth, cam mechanism adapted to move the rear bank of needles into and out of operative position, pickers adapted to move certain needles of the front bank successively out of operative position, pickers adapted to successively move into operative position needles previously rendered inoperative, picker controlling means, and cams carried by the ratchet ring and adapted as the ratchet ring is turned by the pawl, to control the operation of the needle actuating cam mechanism and the picker controlling means.

18. In a circular knitting machine, in combination, a relatively rotatable needle cylinder, a relatively stationary cam ring, rotary driving means, oscillatory driving means, shifting mechanism for alternately connecting the two driving means with the needle cylinder, a ratchet ring arranged concentric with the needle cylinder and having a relatively long tooth and a number of shorter teeth, a pawl actuating the ratchet ring and adapted, during rotation of the needle cylinder, to play back and forth on the long tooth, pattern controlled mechanism adapt-

ed to effect actuating engagement of the pawl with the long tooth, needle actuating devices, and cams carried by the ratchet ring adapted, as the ratchet ring is turned by the pawl, to control the operation of the needle actuating devices.

19. In a circular knitting machine, in combination, a relatively rotatable needle cylinder, a relatively stationary cam ring, 10 rotary driving means, oscillatory driving means, shifting mechanism for alternately connecting the two driving means with the needle cylinder, a ratchet ring arranged concentric with the needle cylinder having teeth 15 of different length, an actuating pawl for the ratchet ring, means to actuate said pawl and in said actuation to impart to it its forward throw in two successive movements whereby the ratchet ring will be operated at 20 different points in the oscillation of the needle cylinder dependent upon whether the pawl engages a relatively short tooth, or a relatively long tooth, pattern controlled mechanism adapted to render the pawl operative 25 to turn the ratchet ring, cam mechanism adapted to move the rear bank of needles into and out of operative position, pickers adapted to move certain needles of the front bank successively out of operative 30 position, pickers adapted to successively move into operative position needles previously rendered inoperative, picker controlling means, pattern controlled mechanism connected with and adapted to partially control the 35 operation of the shifting mechanism, other devices adapted to partially control the operation of the shifting mechanism, and cams carried by the ratchet ring and adapted, as the ratchet ring is turned by pawl, to control 40 the operation of the needle actuating cam mechanism, picker controlling means and the last named devices.

20. In a circular knitting machine, in combination, a relatively rotatable needle cylinder, a relatively stationary cam ring, 45 rotary driving means, oscillatory driving means, shifting mechanism for alternately connecting the two driving means with the needle cylinder, a ratchet ring arranged concentric with the needle cylinder having teeth 50 of different length, an actuating pawl for the ratchet ring, means to actuate said pawl and in said actuation to impart to it its forward throw in two successive movements 55 whereby the ratchet ring will be operated at different points in the oscillation of the needle cylinder dependent upon whether the pawl engages a relatively short tooth or a relatively long tooth, pattern controlled 60 mechanism adapted to render the pawl operative to turn the ratchet ring, needle actuating devices, pattern controlled mechanism connected with and adapted to partially control the operation of the shifting mecha-

nism, other mechanism adapted to partially control the operation of the shifting mechanism, and cams carried by the ratchet ring and adapted, as the ratchet ring is turned by the pawl, to control the operation of the needle actuating devices and the last named 70 mechanism.

21. In a circular knitting machine, in combination, a relatively rotatable needle cylinder, a relatively stationary cam ring, rotary driving means, oscillatory driving 75 means, shifting mechanism for alternately connecting the two driving means with the needle cylinder, a ratchet ring arranged concentric with the needle cylinder having teeth of different length, an actuating pawl 80 for the ratchet ring, means to actuate said pawl and in said actuation to impart to it its forward throw in two successive movements whereby the ratchet ring will be operated at different points in the oscillation 85 of the needle cylinder dependent upon whether the pawl engages a relatively short tooth, or a relatively long tooth, pattern controlled mechanism adapted to render the pawl operative to turn the ratchet ring, cam 90 mechanism adapted to move the rear bank of needles into and out of operative position, pickers adapted to move certain needles of the front bank successively out of operative 95 position, pickers adapted to successively move into operative position needles previously rendered inoperative, picker controlling means, and cams carried by the ratchet ring and adapted as the ratchet ring is turned by the pawl, to control the operation 100 of the needle actuating cam mechanism and the picker controlling means.

22. In a circular knitting machine, in combination, a relatively rotatable needle cylinder, a relatively stationary cam ring, 105 rotary driving means, oscillatory driving means, shifting mechanism for alternately connecting the two driving means with the needle cylinder, a ratchet ring arranged concentric with the needle cylinder having 110 teeth of different length, an actuating pawl for the ratchet ring, means to actuate said pawl and in said actuation to impart to it its forward throw in two successive movements whereby the ratchet ring will be operated at different points in the oscillation 115 of the needle cylinder dependent upon whether the pawl engages a relatively short tooth or a relatively long tooth, pattern controlled mechanism adapted to render the 120 pawl operative to turn the ratchet ring, needle actuating devices, and cams carried by the ratchet ring adapted, as the ratchet ring is turned by the pawl, to control the operation of the needle actuating devices. 125

23. In a circular knitting machine, in combination, a relatively rotatable needle cylinder, a relatively stationary cam ring, rotary

- driving means, oscillatory driving means, shifting mechanism for alternately connecting the two driving means with the needle cylinder, a ratchet ring arranged concentric with the needle cylinder and having a relatively long tooth, a number of relative short teeth and one or more teeth of medium length, an actuating pawl for the ratchet ring, means to actuate said pawl and in said actuation to impart to it in its forward throw two successive movements, whereby 70 when the pawl engages a medium tooth the ring will be turned on the first forward movement of the pawl and when it engages a short tooth the ring will be turned on the second forward movement of the pawl and 75 when it engages the long tooth it will rack idly thereon, a supplemental pawl for initially turning the ratchet wheel to cause the main pawl to be brought into operative engagement with the long tooth, pattern controlled mechanism adapted to actuate the supplemental pawl, needle actuating devices, pattern controlled mechanism connected with and adapted to partially control the operation of the shifting mechanism, other mechanism adapted to partially control the operation of the shifting mechanism, and cams carried by the ratchet ring and adapted, as the ratchet ring is turned by the pawl, to control the operation of the needle actuating devices and the last named mechanism. 80
24. In a circular knitting machine, in combination, a relatively rotatable needle cylinder, a relatively stationary cam ring, rotary driving means, oscillatory driving means, shifting mechanism for alternately connecting the two driving means with the needle cylinder, a ratchet ring arranged concentric with the needle cylinder and having a relatively long tooth, a number of relative short teeth and one or more teeth of medium 85 length, an actuating pawl for the ratchet ring, means to actuate said pawl and in said actuation to impart to it in its forward throw two successive movements, whereby 90 when the pawl engages a medium tooth the ring will be turned on the first forward movement of the pawl and when it engages a short tooth the ring will be turned on the second forward movement of the pawl and when it engages the long tooth it will rack idly thereon, a supplemental pawl for initially turning the ratchet wheel to cause the main pawl to be brought into operative engagement with the long tooth, pattern controlled mechanism adapted to actuate the supplemental pawl, needle actuating devices, and cams carried by the ratchet ring adapted, as the ratchet ring is turned by the pawl, to control the operation of the needle actuating devices and the last named mechanism. 95
25. In a circular knitting machine, in combination, a relatively rotatable needle cylinder, a relatively stationary cam ring, rotary driving means, oscillatory driving means, shifting mechanism for alternately connecting the two driving means with the needle cylinder, a ratchet ring arranged concentric with the needle cylinder and having a relatively long tooth, a number of relative short teeth and one or more teeth of medium length, an actuating pawl for the ratchet ring, means to actuate said pawl and in said actuation to impart to it in its forward throw two successive movements, whereby 100 when the pawl engages a medium tooth the ring will be turned on the first forward movement of the pawl and when it engages a short tooth the ring will be turned on the second forward movement of the pawl and when it engages the long tooth it will rack idly thereon, a supplemental pawl for initially turning the ratchet wheel to cause the main pawl to be brought into operative engagement with the long tooth, pattern controlled mechanism adapted to actuate the supplemental pawl, needle actuating devices, and cams carried by the ratchet ring adapted, as the ratchet ring is turned by the pawl, to control the operation of the needle actuating devices and the last named mechanism. 105
26. In a circular knitting machine, in combination, a relatively rotatable needle cylinder, a relatively stationary cam ring, rotary driving means, oscillatory driving means, shifting mechanism for alternately connecting the two driving means with the needle cylinder, a ratchet ring arranged concentric with the needle cylinder and having a relatively long tooth, a number of relative short teeth and one or more teeth of medium length, an actuating pawl for the ratchet ring, means to actuate said pawl and in said actuation to impart to it in its forward throw two successive movements, whereby 110 when the pawl engages a medium tooth the ring will be turned on the first forward movement of the pawl and when it engages a short tooth the ring will be turned on the second forward movement of the pawl and when it engages the long tooth it will rack idly thereon, a supplemental pawl for initially turning the ratchet wheel to cause the main pawl to be brought into operative engagement with the long tooth, pattern controlled mechanism adapted to actuate the supplemental pawl, needle actuating devices, and cams carried by the ratchet ring adapted, as the ratchet ring is turned by the pawl, to control the operation of the needle actuating devices and the last named mechanism. 115
27. In a circular knitting machine, the combination with a relatively rotatable needle cylinder and a relatively stationary cam ring, of vertically movable needles carried by the needle cylinder, a cam adapted to engage the butts of certain of the needles and draw them down into operative position, a pivoted lever carrying the cam and adapted to swing the cam toward and from the needle, 120
- 60 driving means, oscillatory driving means, shifting mechanism for alternately connecting the two driving means with the needle cylinder, a ratchet ring arranged concentric with the needle cylinder and having a relatively long tooth, a number of relative short teeth and one or more teeth of medium length, an actuating pawl for the ratchet ring, means to actuate said pawl and in said actuation to impart to it in its forward throw two successive movements, whereby 125 when the pawl engages a medium tooth the ring will be turned on the first forward movement of the pawl and when it engages a short tooth the ring will be turned on the second forward movement of the pawl and when it engages the long tooth it will rack idly thereon, a supplemental pawl for initially turning the ratchet wheel to cause the main pawl to be brought into operative engagement with the long tooth, pattern controlled mechanism adapted to actuate the supplemental pawl, needle actuating devices, and cams carried by the ratchet ring adapted, as the ratchet ring is turned by the pawl, to control the operation of the needle actuating devices and the last named mechanism. 130
- 65 driving means, oscillatory driving means, shifting mechanism for alternately connecting the two driving means with the needle cylinder, a ratchet ring arranged concentric with the needle cylinder and having a relatively long tooth, a number of relative short teeth and one or more teeth of medium length, an actuating pawl for the ratchet ring, means to actuate said pawl and in said actuation to impart to it in its forward throw two successive movements, whereby 135 when the pawl engages a medium tooth the ring will be turned on the first forward movement of the pawl and when it engages a short tooth the ring will be turned on the second forward movement of the pawl and when it engages the long tooth it will rack idly thereon, a supplemental pawl for initially turning the ratchet wheel to cause the main pawl to be brought into operative engagement with the long tooth, pattern controlled mechanism adapted to actuate the supplemental pawl, needle actuating devices, and cams carried by the ratchet ring adapted, as the ratchet ring is turned by the pawl, to control the operation of the needle actuating devices and the last named mechanism. 140

cylinder, a second pivoted lever, the axes of both levers being fixed relatively to the cam ring, means whereby the second lever yieldingly actuates the first lever, a turnable member, and a cam fixed thereon adapted, as said member is turned, to positively operate the second lever and thereby, through the latter's yielding connection with the first lever, force the needle-depressing cam into the path of travel of said needle butts.

28. In a circular knitting machine, the combination with a relatively rotatable needle cylinder and a relatively stationary cam ring, of vertically movable needles carried by the needle cylinder, a cam adapted to engage the butts of certain of the needles and draw them down into operative position, a pair of levers, one carrying the cam and the other pivoted on the first lever, a spring between the levers whereby when the second lever is moved on its pivot toward the first lever, the latter will be yieldingly actuated to force the needle-depressing cam inward into the path of travel of said needle butts, a turnable member, and a cam on the turnable member adapted, as said member is turned, to positively actuate the second lever.

29. In a circular knitting machine, the combination with a relatively rotatable needle cylinder and a relatively stationary cam ring, of vertically movable needles carried by the needle cylinder, a cam adapted to engage the butts of certain of the needles and draw them down into operative position, a pivoted lever whose axis is fixed relatively to the cam ring, said cam being carried by said lever, a second slotted lever supported on the first lever, an arm on the first lever extending into the slot of the second lever, a spring coiled about said arm and confined between the two levers, a turnable member, a cam fixed on the turnable member, and a cam on the second lever adapted as said member is turned, to be actuated by the cam on the turnable member to move the second lever toward the first lever and thereby compress said spring and yieldingly force the needle-depressing cam inward into the path of travel of said needle butts.

30. In a circular knitting machine, the combination with a relatively rotatable needle cylinder and a relatively stationary cam ring, of a rotatable ratchet ring, means to turn the same, vertically movable needles carried by the needle cylinder, a pair of pickers adapted to engage certain of said needles and move them successively out of operative position, a pair of levers, one for each picker, controlling the movement of said pickers into and out of operative position, said levers being connected to move in unison, and a cam on the ratchet ring adapted to actuate one of said levers.

31. In a circular knitting machine, the combination with a rotatable needle cyl-

inder and a relatively stationary cam ring, of a rotatable ratchet ring, means to turn the same, vertically movable needles carried by the needle cylinder, a pair of pickers adapted to engage certain of said needles and move them successively out of operative position, a pair of two-armed levers pivoted on stationary axes, two corresponding arms of the two levers having a pin and slot connection, and the other two corresponding arms of the two levers adapted to control the pickers, and a cam on the ratchet ring adapted to engage one of said levers and move and hold both levers in operative position.

32. In a circular knitting machine, the combination of a stationary cam cylinder, a rotatable needle cylinder and vertically movable needles carried thereby, two independently operable pickers adapted to move certain needles successively out of action, springs, one for each picker, normally holding them in operative position, a pair of levers connected to move in unison and acting when operative to hold the two pickers in inoperative position against the action of their springs, a member revoluble independently of the needle cylinder, means to turn said member intermittently, and a cam on said member adapted to control the operation of said levers.

33. In a circular knitting machine, the combination of a stationary cam cylinder, a rotatable needle cylinder and vertically movable needles carried thereby, two independently operable pickers adapted to move certain needles successively out of action, springs, one for each picker, normally holding them in operative position, a pair of levers connected to move in unison and acting when in one position to hold the pickers in inoperative position against the action of their actuating springs and in another position to release the pickers, a member revoluble independently of the needle cylinder, means to turn said member intermittently, and a cam on said member and a spring connected with said levers, one for moving said levers into, and the other for moving them out of, their holding positions.

34. In a circular knitting machine, in combination, a rotatable needle cylinder, a relatively stationary cam ring, rotary driving means, oscillatory driving means, shifting mechanism for alternately connecting the two driving means with the needle cylinder, a rotatable ratchet ring, means to turn the same during oscillation of the needle cylinder, means controlled by the ratchet ring to move certain of the needles successively out of operative position, pickers adapted to successively return the needles into operative position, and means connected with the pickers and adapted to be operated independently of the ratchet ring by said

shifting mechanism, in the shift from oscillation to rotation, to effect the withdrawal of the pickers from operative position.

35. In a circular knitting machine, the combination with a relatively rotatable needle cylinder and a relatively stationary cam ring, of rotary driving means; oscillatory driving means, shifting mechanism for alternately connecting the two driving means with the needle cylinder, a rotatable ratchet ring, means to turn the same during oscillation of the needle cylinder, means to move certain of the needles successively out of operative position, pickers adapted to successively return the needles into operative position, a cam on the ratchet ring, means connected with the pickers adapted to be operated by said cam to move the pickers out of operative position in the shift from oscillation to rotation, and means connected with the pickers and adapted to be operated by the shifting mechanism.

36. In a circular knitting machine, the combination with a relatively rotatable needle cylinder and a relatively stationary cam ring, and means to oscillate the needle cylinder, of means to elevate certain of the needles successively out of operative position, pickers adapted to be engaged by certain of said elevated needles and be moved thereby in the direction of movement of the needles, guides adapted to coöperate with the pickers to cause the latter to carry the engaged needles downward into operative position, a lever movable with each picker, and a projection turning with the needle cylinder adapted, in the latter's oscillation, to actuate said lever and return the picker to its operative position.

37. In a circular knitting machine, the combination with a relatively rotatable needle cylinder and a relatively stationary cam ring, of means to elevate certain of the needles successively out of operative position, a pair of pickers adapted to be engaged by certain of the elevated needles moving respectively in opposite directions and to be moved thereby in the direction of movement of the needles, guides adapted to coöperate with the pickers to cause the latter to carry the engaged needles downward into operative position, a lever movable with each picker, a projection turning with the needle cylinder adapted, in the latter's oscillation, to actuate first one lever and then the other to successively restore the pickers to operative position, and means to move both levers out of operative relation with said projection whereby the pickers are caused to remain in inoperative position.

38. In a circular knitting machine, the combination with a relatively rotatable needle cylinder and a relatively stationary cam ring, and means to oscillate the needle cylinder, of means to elevate certain of the needles successively out of operative position, pickers adapted to be engaged by certain of the elevated needles and be moved thereby in the direction of movement of the needles, guides adapted to coöperate with the pickers to cause the latter to carry the engaged needles downward into operative position, a lever movable with each picker, connections between said levers arranged to cause them to move in unison, said levers being also movable independently to return the respective pickers to operative position, a projection turning with the needle cylinder adapted, in the latter's oscillation, to actuate said levers alternately and impart to them said independent movements, and means to operate said connections and thereby actuate both levers to render their respective pickers inoperative.

39. In a circular knitting machine, the combination with a relatively rotatable needle cylinder and a relatively stationary cam ring, of means to elevate certain of the needles successively out of operative position, pickers each having a cam face adapted to engage certain of said needles successively and to be moved thereby in the direction of movement of the needles, a frame having a plurality of guiding slots, pins on each picker engaging the slots respectively and coöperating therewith to turn the picker and change the angle of its cam face to allow the engaged needles to be moved down into operative position and disengaged, a slotted lever engaged by one of said pins and actuated thereby in the movement of the picker, and a projection turning with the needle cylinder adapted to engage said lever and restore the corresponding picker to operative position.

40. In a circular knitting machine, the combination with a relatively rotatable needle cylinder and a relatively stationary cam ring, of means to elevate certain of the needles successively out of operative position, pickers each having a cam face adapted to engage certain of said needles successively and to be moved thereby in the direction of movement of the needles, a frame having a plurality of guiding slots, pins on each picker engaging the slots respectively and coöperating therewith to turn the picker and change the angle of its cam face to allow the engaged needles to be moved down into operative position and disengaged, a pair of pivoted levers, a second pair of levers each pivoted to one of the first levers and slotted to engage one of the pins of one of the pickers, a pair of fixed pins, a cam face on each of the slotted levers engaging one of said pins, the first named pair of levers being connected together to move in unison, and means adapted to actuate the first named pair of levers and thereby cause each of the slotted levers to slide along one of the fixed

pins and thereby move each of the pickers out of operative position.

41. In a circular knitting machine, the combination with a relatively rotatable needle cylinder and a relatively stationary cam ring, of means to elevate certain of the needles successively out of operative position, pickers each having a cam face adapted to engage certain of said needles successively 10 and to be moved thereby in the direction of movement of the needles, a frame having a plurality of guiding slots, pins on each picker engaging the slots respectively and coöperating therewith to turn the picker 15 and change the angle of its cam face to allow the engaged needles to be moved down into operative position and disengaged, a pair of pivoted levers, a second pair of levers each pivoted to one of the first levers 20 and slotted to engage one of the pins of one of the pickers actuated thereby in the movement of the picker, a projection turning with the needle cylinder adapted to engage each slotted lever and swing it on its 25 pivot and thereby restore the corresponding picker to operative position, a pair of fixed pins one for each slotted lever, a cam face on each slotted lever engaging one of the pins, the first named pair of levers being connected together to move in unison, and means adapted to actuate the first named pair of levers and thereby cause each of the slotted levers to slide along one of the fixed pins and thus be withdrawn from 30 the path of travel of the projection on the needle cylinder while at the same time withdrawing the corresponding picker from operative position.
42. In a circular knitting machine, the combination with a relatively rotatable needle cylinder and a relatively stationary cam ring, and means to oscillate the needle cylinder, of a rotatable ratchet ring, means to turn the same during oscillation of the 40 needle cylinder, means to elevate certain of the needles successively out of operative position, pickers adapted to be engaged by certain of said elevated needles and be moved 45

thereby in the direction of movement of the needles, guides adapted to coöperate with the pickers to cause the latter to carry the engaged needles downward into operative position, a lever movable with each picker, a projection turning with the needle cylinder adapted, in the latter's oscillation to actuate said lever and return the picker to its operative position, and a cam on the ratchet ring adapted to move said lever out of the path of travel of said projection and simultaneously render the corresponding picker 55 inoperative.

43. In a circular knitting machine the combination with a rotatable needle cylinder and a relatively stationary cam ring, of rotary driving means, oscillatory driving means, shifting mechanism for alternately connecting the two driving means with the needle cylinder, a rotatable ratchet ring, means to turn the same during oscillation of the needle cylinder, means to elevate certain of the needles successively out of operative position, 60 pickers adapted to be engaged by certain of said elevated needles and be moved thereby in the direction of movement of the needles, guides adapted to coöperate with the pickers to cause the latter to carry the engaged needles downward into operative position, a lever movable with each picker, a projection turning with the needle cylinder adapted, in the latter's oscillation to 65 actuate said lever and return the picker to its operative position, and means connected with said lever and adapted in the shift from oscillation to rotation, to be actuated by said shifting means to move the lever 70 out of the path of travel of said projection, thereby simultaneously withdrawing the 75 picker from operative position.

In testimony of which invention, we have hereunto set our hands at Phila., Pa., on 80 this 27th day of March, 1913.
